Attorney

Patented Sept. 23, 1924.

UNITED STATES PATENT OFFICE.

GEORGE W. HEISE, OF ELMHURST, NEW YORK, ASSIGNOR TO NATIONAL CARBON COMPANY, INC., A CORPORATION OF NEW YORK.

HERMETICALLY-SEALED DRY CELL.

Application filed June 30, 1921. Serial No. 431,715.

To all whom it may concern:

Be it known that I, GEORGE W. HEISE, a citizen of the United States, residing at Elmhurst, in the county of Queens and State of New York, have invented certain new and useful Improvements in Hermetically-Sealed Dry Cells, of which the following is a specification.

This invention relates in general to the prevention of detrimental gas pressure in dry cells. More specifically, it comprises the use of reagents capable of fixing gases evolved in hermetically sealed cells during their storage or "shelf-life" period.

It is known that the pre-service deterioration of dry cells is due in large part to the non-hermetic character of the seal. Moisture continuously escapes through crevices between the seal and the electrodes or through the pores of the carbon rod, and it is probable also that air enters through these openings, increasing zinc corrosion by depolarizing the centers of local action.

Heretofore it has been regarded as impracticable to provide a true hermetic seal on dry cells of standard construction and reagent composition because of the evolution of gases, due to local action, decomposition of the mix, or other causes. Unless these gases find an exit, the internal pressure may become sufficient to distort or rupture some portion of the cell. It is an object of the present invention to provide a hermetically sealed cell in which the generation of excessive gas pressure is prevented. This object is attained by sealing to the cell a removable impervious cap which may be so constructed as to form an expansion chamber having a volume adequate to receive cell gases without an excessive development of pressure.

Reagents capable of fixing the evolved gases in the form of compounds having low vapor pressure at ordinary temperature may be used in such caps as an additional protection against the accumulation of gases. Or, when the reagent employed is an active absorbent, it may be supplied in a sealing cap of relatively small volume.

The invention will be described in detail in connection with the accompanying drawing, in which—

Fig. 1 is a vertical longitudinal section through a hermetically sealed cell,

Fig. 2 is a fragmentary side elevation showing the sealing means, and

Fig. 3 is a vertical longitudinal section through a cell having a modified form of cap which contains a gas absorbent.

Reference numeral 1 denotes a zinc container, 2 a lining of bibulous material and 3 a mix bobbin containing a carbon rod 4. The zinc container has a marginal depression 5 to which a binding post may be attached so as to lie wholly within the outline of the container. A plastic seal 6 of the usual type is provided. This seal is non-hermetic but is sufficiently close fitting to prevent undue evaporation of moisture after the removal of the absolutely airtight closure now to be described.

The hermetic seal comprises a cap 7, of metal or other impervious material, having a cross section corresponding to that of the container 1. The cap and container, placed with their margins in abutting relation, are secured together by means of a band 8 overlying their junction. The band 8 may be attached in any manner which will give a secure and air-tight joint, as, for example, by soldering it to both the cap and container. A tongue 9 is provided on the band 8 and is adapted to be passed through an opening 10 in key 11. When it is desired to remove the hermetic sealing cap 7, the band may be severed by engaging the tongue in the key and rotating the latter to tear the metal along the lines of the sides of the tongue extended, in a well known manner. A clip 12 may be provided on the top of cap 7, or elsewhere on the cell, for holding the key in handy position.

The cap 7 preferably has a volume about five times as large as the volume of gas, measured at atmospheric temperature and pressure, which will normally be evolved from the cell contents. Experience has shown that a cap about 1½ inches in height is suitable for application to a 6 inch cell, and the same relative proportions may be used in sealed cells of other sizes. The volume of a cap of this type is relatively very large as compared to the interstitial volume below the pitch inner seal. Such an expansion chamber is capable of receiving without undue strain a quantity of gas which would exert a distorting or disrupting pressure if confined below the inner

5 seal. The cap is preferably made of thinner metal than the usual zinc can and is formed with a concave top which can spring outwardly into convex shape to enlarge the expansion chamber, should the pressure of the gas require it.

10 I have discovered that the principal cause of gas pressure in hermetically sealed cells is the formation of carbon dioxide by interaction of the mix and electrolyte. Local action upon the zinc is substantially prevented by sealing the cell from contact with air, so that the hydrogen production is negligible. As carbon dioxide is the only 15 gas which under ordinary conditions is likely to cause excessive pressure, hermetically sealed cells may be adequately protected by the use of an alkaline absorbent. Hydrated lime may be mentioned, by way of example, 20 as a suitable material. A large number of alkaline solids capable of reacting with carbon dioxide at ordinary temperatures are known, however, and my invention includes the use of any of these bodies.

25 As shown in Fig. 3, a cap 13 is sealed upon a cell in the manner described above. A material 14, such as lime, is contained in the cap and is preferably spaced from the carbon electrode by an inverted cup 15 of heavy paper or the like. The use of alkaline liquids as absorbents of carbon dioxide is also within the scope of my invention. When these are used, any suitable precautions may be taken to prevent electrical connection between the carbon and zinc poles.

30 Another convenient way of fixing carbon dioxide is by the use of ammonia gas. This may be introduced into the cap in a variety of ways, for example by evacuating the cap through a suitable opening, passing in ammonia, and sealing the opening. Carbon dioxide evolved from the mix will pass through crevices between the plastic seal 6 and the electrodes, or through pores in the carbon rod and spacing cup 15, into contact and combination with the ammonia, lime, or other absorbent.

35 Instead of supplying a material capable of reacting with carbon dioxide, the same ultimate result may be obtained by the use of any gas or vapor which will react chemically with a constituent of the cell to produce a solid or liquid compound. In this manner a reduction of the volume of gas contained within the cell is effected and a corresponding increment of carbon dioxide or other evolved gas will not increase the pressure. The sealing cap may, for example, be filled with oxygen. This gas combines in a relatively short time with hydrogen produced by local action on the zinc, the corrosion of the metal being accelerated by the presence of the oxygen, or it may be 40 fixed in other ways, as by the formation of

zinc oxid. The reduction of pressure within the cell produced by the union of oxygen with hydrogen, zinc, or other substances is appreciable even when the cap contains air. The amount of oxygen in the cap is insufficient to produce the harmful effects which would be caused by continued ingress of air, if the seal were non-hermetic. In some cases, also, ammonia supplied as described above, may react to form compounds with zinc chloride or other cell constituent, before having opportunity to combine with carbon dioxide. The result of such reaction is a reduction of gas volume compensating for subsequent generation of gases in the cell.

45 When the cell is to be put in service, the sealing cap will be disconnected as described and the spacing cup removed from its position over the carbon pole. The service characteristics of cells so protected from the deleterious effects of loss of moisture, access of atmospheric oxygen, or other causes due to incomplete isolation from the atmosphere, will be found substantially equal to those of freshly prepared cells.

50 The above described expedients for preventing gas pressure may be used singly or in any desired combination according to the requirements of any particular case. If gases other than carbon dioxide are given off in objectionable quantities, a suitable specific absorbent for such gases may be readily selected in accordance with known chemical properties. Some of the beneficial results of my invention may be obtained in 55 non-hermetically sealed cells, as, for example, by placing a layer of gas absorbent material below the pitch seal. The shape and mode of attachment of the sealing cap may also be modified to fit it for use with cells 60 of non-cylindrical type, and various other changes in construction and relative arrangement of parts may be made within the scope of the appended claims.

65 I claim:

1. A dry cell containing a material capable of reacting chemically with a substance in said cell to produce a reduction of pressure in said cell.
2. A dry cell containing a material capable of preventing excessive gas pressure therein by chemical combination with gas evolved from cell constituents.
3. A dry cell containing an alkaline absorbent material capable of fixing gas evolved in said cell.
4. A hermetically sealed dry cell containing an alkaline absorbent material capable of fixing carbon dioxide evolved in said cell.
5. A hermetically sealed dry cell containing lime disposed so as to take up gas evolved in said cell.
6. In a dry cell, a seal permitting the passage of gases, an air-tight cap enclosing said seal, and a material in said cap capable of

reacting chemically with gases generated in the cell.

7. In a dry cell, a hermetic seal comprising a cap having a volume adapting it to serve as an expansion chamber for gases generated within the cell.

8. In a dry cell, a seal permitting the passage of gases, an air-tight cap enclosing said seal, and a material in said cap capable of reacting chemically with gases generated in the cell, said cap having a top capable of yielding without rupture under gas pressure.

9. In a dry cell, a seal permitting the passage of gases, an air-tight cap enclosing said seal, and a material in said cap capable of reacting chemically with gases generated in the cell, said cap having a top capable of yielding without rupture under gas pressure. 15

In testimony whereof, I affix my signature.

GEORGE W. HEISE.
